Primary Examiner — Wan Laymon(74) *Attorney, Agent, or Firm* — McAndrews, Held & Malloy, Ltd.(57) **CLAIM**

The ornamental design for an orthodontic appliance, as shown and described.

DESCRIPTION

FIG. 1 is a top right rear perspective view of an orthodontic appliance showing my new design;

FIG. 2 is a top right front perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines illustrate portions of the orthodontic appliance that form no part of the claimed design.
